UNITED STATES PATENT OFFICE.

ALEXANDER McLANE, OF LANSFORD, AND JOHN CHURNISIDE, OF HUDSON,
PENNSYLVANIA.

DETACHABLE CONNECTOR.

1,143,218.

Specification of Letters Patent. Patented June 15, 1915.

Application filed July 17, 1914. Serial No. 851,479.

To all whom it may concern:

Be it known that we, ALEXANDER McLANE and JOHN CHURNISIDE, citizens of the United States of America, and residents of Lansford, in the county of Carbon and State of Pennsylvania, and Hudson, in the county of Luzerne and State of Pennsylvania, respectively, have invented certain new and useful Improvements in Detachable Connectors, of 10 which the following is a specification.

Our invention relates to improvements in connectors and is particularly intended for use in connection with hinges, making the hinge what is known as a "demountable hinge"; but our improved connector is also adapted for use separate from hinges, as hereinafter described.

Our invention comprises improved means whereby a door, gate, panel, partition or the like may be mounted and dismounted easily and rapidly without the driving or removal of screws, nails, or the like, and without marring of either the door, gate, panel, etc., or the support on which such door, gate, 25 panel, etc., is to be mounted or from which it is to be removed.

Our invention consists in the novel connector hereinafter described and illustrated in certain embodiments in the accompanying drawings.

The object of our invention is to provide a simple and inexpensive connector whereby doors, gates, panels, partitions, etc., may be mounted and dismounted quickly and 35 readily, and without injury to themselves or to the parts to which they are to be connected or from which they are to be disconnected.

We will now proceed to describe our invention with reference to the accompanying drawings, and will then point out the novel features in claims.

In the drawings: Figure 1 shows a front view of a portion of a door and door-frame 45 united by a hinge provided with a connector embodying our invention. Fig. 2 shows an elevation of the same parts with the door swung outward and lifted preparatory to dismounting, the hanger plate forming a 50 part of the connection being shown in vertical section. Fig. 3 shows an elevation of a portion of the door and door frame, with

the door separated from the door frame, the hinge and the hanger plate being both shown in elevation, but detached one from 55 the other. Fig. 4 shows a transverse vertical section of the demountable hinge shown in Figs. 1-3 inclusive, and of the door frame or other support to which the hanger plate is shown as connected in Figs. 60 1, 2 and 3, the section being taken on the line $x-x$ of Fig. 1, the scale of Fig. 4 being larger than that of Figs. 1, 2 and 3. Fig. 5 shows a transverse vertical section of a demountable hinge embodying an alternative 65 form of hanger plate, the section being taken on the line $y-y$ of Fig. 6. Fig. 6 shows an elevation of a demountable hinge embodying the form of hanger plate shown in Fig. 5, the said hanger plate being shown 70 in longitudinal vertical section. Fig. 7 shows a front view of a plain (*i. e.*, non-hinged) connector, and of portions of panels to which such connector is attached. Fig. 8 is a view similar to Fig. 1 but shows an 75 alternative form of demountable hinge.

Referring first to Figs. 1-4 inclusive, 1 designates a door frame or like support, 2 a door in operative relation to said door frame, and 3 and 4 designate leaves of a 80 hinge connecting such door and door frame, the leaf 4 of the hinge fitting within a hanger plate 5, which hanger plate is secured to the door frame 1, by suitable fastenings, for example, screws 6. The leaf 4 of the hinge 85 is provided with slots 7, shown in this case as of approximate L-form, and with hooks 8 complementary to said slots, which hooks 8 engage the shanks of the screws 6. With the leaf 4 and hanger plate 5 in engagement as 90 shown in Figs. 1 and 4, there is a sufficient clearness between the top of the hinge leaf 4 and the top of the hanger plate 5 to permit the lifting of the door 2 with the hinge 3-4 thereon, so that the ends of the hooks 8 clear 95 the shanks of the screws 6. It will be clear that, with the hinge and hanger plate locked together as shown in Figs. 1 and 4, such hinge and hanger plate may be disconnected by lifting the hinge with reference to the 100 hanger plate until the hooks 8 clear the screws 6, and then drawing the hinge leaf 4 out of the hanger plate. Fig. 2 shows the door 2, and the hinge 3-4, so lifted, prepara-

tory to the drawing the hinge leaf 4 out of the hanger plate, the door 2 having been swung out to permit such withdrawal of the hinge leaf 4 from the hanger plate. Fig. 3 5 shows the parts after disconnection. It will be apparent that by a reverse operation the hinge and the hanger may be connected again, the door, with the hinge thereon, being raised so that the hinge leaf 4 may be 10 inserted into the hanger plate, with the hooks 8 passing the shanks of the screw 6, and the door being lowered after such insertion, so that the hooks 8 engage the shanks of the screw 6. It will also be apparent that 15 the screws 6 form the support both for the hinge and the door which it carries, and for the hanger plates. The hanger plates properly space apart and reinforce the screws and in addition serve to cover the slots and 20 hooks on the hinge leaf both at the front and at the back. Moreover, with the alined slots 7 of the leaf 4 engaging the screws which are also alined, the weight of the door is divided between the two screws and slots 25 and the slots and hinge are held rigidly in position. Relative lateral movement of the hanger plate and hinge is thus prevented except when removing the hinge or inserting it in place.

30 The hanger plate, it will be seen, may be permitted to remain permanently connected to the door frame 1 while the hinge 3—4 may remain permanently connected to the door 2, the parts being capable of connection or disconnection without the driving or removal of screws, nails or the like, once the hinge has been properly connected to the door and the hanger plate has been properly connected to the doorway; marring of the 35 door and doorway being thereby avoided; and as will be obvious, the hanger plate may be of such neat and ornamental appearance that its presence, after removal of the door, will be in no wise detrimental.

40 Various uses for a demountable hinge such as illustrated will readily occur to those skilled in the art; among which will naturally be the use of such a hinge in connection with screen-doors, storm-doors, swinging 45 window screens and sashes, temporary gates and doors, or gates and doors which are subject to removal from time to time, etc.

50 In Figs. 5 and 6 we illustrate an alternative construction of the demountable hinge, differing from that previously illustrated and described, in that the hanger plate, here designated by numeral 5^a, comprises a back member 5^b, the hanger plate being, therefore, closed at the back, whereas 55 the hanger plate shown in Figs. 1-4 inclusive is open at the back. In Figs. 5 and 6 we have also shown the hanger plate 5^a as provided with bosses 9 connecting the front and back walls of the hanger, and apertured 60 for the passage of the fastening screws; the

hooks 8 of the hinge leaf 4 being arranged to engage these bosses 9, instead of engaging the screws direct.

The construction of Figs. 5 and 6 is somewhat more substantial than that of Figs. 1-4 inclusive, but, also, is somewhat more expensive. In this construction also as well as in that of Figs. 1 to 4, the screws form the support both for the hinge and door through the bosses 9, and for the hanger plate, the slots 7 and hooks 8 acting directly against the screws through the bosses 9. The same rigidity and prevention of relative lateral movement of the hinge and hanger plate is secured in this construction that is referred to in connection with the construction of Figs. 1 to 4. The hooks and slots are similarly concealed so that no uneven projections are visible, both the front and back side of the hanger plate presenting a smooth unbroken surface.

Obviously, our improved connector is not limited to use in connection with a hinge, but may be employed as a plain connection for members, such as partition panels, screen panels, etc., which, it may be desirable to disconnect or dismount from time to time. Such connector is shown in Fig. 7, wherein the hanger plate 5 is of the construction shown in Figs. 1-4 inclusive, but the hooked member coöperating with such hanger plate, here designated by numeral 4^x, is a simple plate having slots 7 and hooks 8 the same as the hinge leaf 4 of Figs. 1-4 inclusive. It will be obvious that this connector shown in Fig. 7 is used in the same manner as are the connectors shown in Figs. 1-6 inclusive. It will also be apparent that similar advantages are secured as when the connector is used in connection with door hinges. The provision of a plurality of screws or lugs in the hanger plate, and of a plurality of complementary hooks and slots in the co-operating hook member, prevents relative movement of the panels, etc., except when inserting and removing the hook member.

It will be obvious that, and as shown in Fig. 8, the hooks, there designated by numeral 8^x, might be provided on the hanger plate, and arranged to engage lugs 6^x provided on a hinge leaf, there designated by numeral 4^w; however, this construction of Fig. 8, while practicable, is not considered as desirable as the construction shown in Figs. 1-6 inclusive, since it is not desirable, 115 ordinarily, to provide a member which is to remain permanently attached to a door frame or the like, with such projections as the hooks 8^x. The relative rigidity of the hook member or hinge leaf and hanger plate 120 are nevertheless retained in this construction, as well as in the other constructions 125 illustrated and described.

It will also be obvious that our improved connector may be made in various different 130

forms and for various different purposes and that the constructions herein illustrated and described are only specific embodiments of an invention susceptible of embodiment 5 in very many different forms.

What we claim is:—

1. A connector such as described, comprising a hanger plate adapted to be secured to a suitable support and a connector plate 10 adapted to be supported by said hanger plate and in turn itself to act as a support, said hanger plate having an intermediate supporting lug and a front plate extending to both sides of said lug, and said connector 15 plate having a supporting hook and complementary slot adapted to engage said lug behind said plate, whereby the lug, hook and slot are hidden from view by said front plate.
2. A connector such as described, comprising a hanger plate adapted to be secured to a suitable support and a connector plate adapted to be supported by said hanger plate and in turn itself to act as a support, 20 said hanger plate having front and side plates and a plurality of intermediate supporting lugs, and said connector plate having a plurality of corresponding supporting hooks and complementary slots adapted to 25 engage said lugs, said lugs, hooks, and slots being hidden from view by said front and side plates.
3. A connector such as described, comprising a hanger plate adapted to be secured to a suitable support and a connector plate 30 adapted to be supported by said hanger plate and in turn itself to act as a support, said hanger plate having a front plate provided with an intermediate opening for the 35 passage of an attaching means and with means for spacing said front plate from the hanger plate support to provide a recess behind said plate, and said connector plate being provided with a hook and complementary slot, adapted to aline with said intermediate opening, said hook and slot being 40 hidden from view by said front plate, and said hanger plate and connector plate being adapted to be supported by said attaching 45 means.
4. A connector such as described, comprising a hanger plate adapted to be secured to a suitable support and a connector plate adapted to be supported by said hanger 50 plate and in turn itself to act as a support, said hanger plate having a front and back

plate provided with an intermediate transverse opening for the passage of an attaching means and with means for spacing said front and back plates apart to form an intermediate recess adapted to receive the connector plate, said connector plate having a hook and complementary slot adapted to aline with said intermediate opening, said hook and slot being hidden from view by 60 said front plate, and said hanger plate and connector plate being adapted to be supported by said attaching means.

5. A demountable hinge such as described, comprising a hanger plate adapted to be secured to a suitable support, and a hinge leaf adapted to be supported by said hanger plate, said hanger plate having a front plate provided with a plurality of intermediate openings for the passage of supporting 70 means and with means for spacing said front plate from the hanger plate support to provide a recess behind said plate, and said hinge leaf being provided with a plurality of corresponding hooks and complementary slots adapted to aline with said intermediate openings, said hooks and slots being hidden from view by said front plate, and said hanger plate and hinge leaf being 75 adapted to be supported by said attaching means.

6. A demountable hinge such as described, comprising a hanger plate adapted to be secured to a suitable support and a hinge leaf adapted to be supported by said hanger 90 plate, said hanger plate having front and back plates provided with a plurality of intermediate transverse openings for the passage of attaching means and with means for spacing said front and back plates apart to 95 form an intermediate recess adapted to receive the hinge leaf, said hinge leaf having a plurality of hooks and complementary recesses adapted to aline with said intermediate openings, said hooks and slots being hidden from view by said front plate, and said hanger plate and hinge leaf being adapted to be supported by said attaching means.

In testimony whereof we have signed this specification in the presence of two subscribing witnesses.
